COMBINED PYROPHORIC LIGHTER AND CIGARETTE CONTAINER

Louis V. Aronson, Newark, N. J., assignor to Art Metal Works, Inc., a corporation of New Jersey

Application December 2, 1935, Serial No. 52,479

5 Claims. (Cl. 206—41.4)

My invention relates to a combined pyrophoric lighter and cigarette container.

My invention has further reference to a combined device which is constructed in a novel manner so that movement of the pyrophoric lighter fuel casing with respect to the cigarette container opens the latter for the removal of a cigarette.

My invention has further reference to pyrophoric lighter mechanism arranged in a novel manner with respect to a cigarette container so as to be efficiently utilized as a smoker's article.

Various other objects, advantages and characteristics of my invention will become apparent from the following detailed description.

My invention resides in the combined device, pyrophoric lighting mechanism, features, combinations and arrangements of the character hereinafter described and claimed.

For an understanding of my invention and for an illustration of one of the many forms thereof, reference is to be had to the accompanying drawing, in which:

Figure 1 is a perspective view of the combined device of my invention;

Fig. 2 is a perspective view of the combined device with the cigarette container in open position;

Fig. 3 is a front elevational view, partly in section, showing the combined device with the cigarette container in open position;

Fig. 4 is a transverse vertical sectional view, partly in elevation, and is taken on the line 4—4 of Fig. 3; and

Fig. 5 is an enlarged, transverse horizontal sectional view, partly in plan, and is taken on the line 5—5 of Fig. 3 looking in the direction of the arrows.

Referring to the drawing, C represents a cigarette container or casing and C1 represents a fuel casing for a pyrophoric lighter, these two casings being associated in the manner herein-after described.

The cigarette container C comprises a base section 1 and a cover section 2, these two sections being of similar square or rectangular receptacle-like configuration as shown. The cover section 2 is pivoted to the base section 1 along those adjacent edges thereof which are removed to the greatest extent from the fuel casing C1. To this end, any suitable arrangement may be utilized such, for example, as illustrated wherein the base section 1 comprises a plurality of spaced ears 1a and the cover section 2 comprises a similar set of spaced ears 2a, these ears being provided with

passages which may be aligned as shown for the reception of a pivot rod 3.

As illustrated in Figs. 2 and 3, a retaining member 4 is disposed interiorly of the cigarette container C, this member 4 being provided with an ear 4a provided with a passage through which the rod 3 passes whereby the member 4 has free pivotal connection on said rod 3. Immediately adjacent one side of the ear 4a, the rod 3 is exposed so that a spring 5 may be coiled there-around, one end of this spring 5 engaging the member 4 and the other end of said spring engaging the cover section 2 as shown. This spring 5, therefore, has a dual function. It effectively biases the member 4 toward the base section 1 as indicated in Fig. 2 and it also tends to bias the cover section 2 toward open position as illustrated in Figs. 2 and 3.

As shown in Fig. 5, the base section 1 comprises a lateral section 1b and the cover section 2 comprises a similar lateral section 2b, these two lateral sections forming that wall surface of the cigarette container C which is opposite the pivotal connection formed by the rod 3. As illustrated in Figs. 3 and 5, the fuel casing C1 comprises a wall 6 which is disposed in generally parallel relation with respect to the aforesaid lateral sections 1b and 2b when they are closed upon each other. However, this wall 6 does not directly engage said lateral sections 1b and 2b inasmuch as said wall 6, on all sides thereof, terminates in lateral flanges 6a which extend closely adjacent the aforesaid lateral sections 1b and 2b of the container C.

Further as illustrated in Figs. 3 and 5, a clamp 7 is soldered or otherwise suitably secured to the exterior surface of the casing wall 6, this clamp comprising an angular section 7a which extends loosely through a slot formed in the adjacent lateral section 1b, said angular section 7a terminating in hook sections 7b, Fig. 4, which are clamped around a spring rod 8 disposed at one side of the lateral section 1b. As clearly shown in Fig. 3, the rod 8 is of bow configuration and is disposed in engagement with the angular section 7a only at opposite sides of the clamp 7.

The spring rod 8 tends to keep the casing C1 seated upon the angular sections 7a and 7b of the casing C in the manner shown by the full lines in Fig. 5. However, the casing C1 may be moved manually in a counter-clockwise direction, Fig. 5, as shown by the broken lines, the rear flange 6a pivoting at 6b on the adjacent surface of the lateral section 1b. In so doing, the spring bar 8 is straightened to some extent. When the man-

ual pressure is removed, said spring bar 8 returns to its illustrated position and reseats the casing C1 as shown by the full lines in Fig. 5. If necessary, the outer surface of the angular section 1b may carry spaced stabilizing lugs 1c which are disposed in alinement and form fixed stops with which the aforesaid rear flange 6a engages during the above described pivotal movement of the casing C1.

10 As shown on the drawing, the outer surface of the aforesaid angular section 2b has a plurality of spaced latching lugs 2c secured thereto and projecting therefrom. When the cover section 2 is in closed position as shown in Fig. 5, the latching lugs 2c are engaged by the interior surface of the front flange 6a of the casing C1. Accordingly, with the parts positioned as just described, the cover section 2 of the container C is latched in closed position.

20 When the container C is to be opened, the combined device is supported in one hand of the user in such manner that the cover section 2 is free to move to open position. Thereupon, the casing C1 is manually operated to move the same with 25 respect to the container C in such manner that the rear flange 6a thereof pivots at 6b. In so doing, the front flange 6a of the casing C1 moves to such position that it is disengaged from the latching lugs 2c of the cover section 2. When 30 this happens, the spring 5 automatically swings the cover section 2 to open position.

35 As soon as the container C has been opened as just described, the manual pressure previously exerted on the casing C1 is removed whereupon said casing C1, under the influence of the spring bar 8, returns to its normal position as shown in Figs. 2 and 3. When the cover section 2 is returned to its closed position, the inclined surfaces of the latching lugs 2c engage the lower edge of 40 the casing front flange 6a and move the casing C1 slightly by a camming action so as to permit the cover section 2 to return to its fully closed position. As soon as said cover section 2 thus 45 returns to the position last noted, the casing C1 returns to its normal position, as shown by the full lines in Fig. 5, so that the cover section 2 of the container C is latched in its closed position.

50 Pyrophoric lighting mechanism of any suitable character may be associated with the above described fuel casing C1. A preferred form of such mechanism and a preferred way of arranging the same on the casing C1 is herein shown. Thus, as illustrated, the fuel casing C1 comprises outer walls 9 and 10 related to each other at right angles so as to form a corner of the combined device. The fuel casing C1 also comprises a wall 11 which is disposed in parallel relation with respect to the wall 9 and which, further, is arranged at right angles to the wall 10. However, as shown, the wall 11 is stepped or disposed inwardly of the outer surface of the container C1 so as to form an offset recess for the reception of the lighting mechanism per se.

55 A pair of wall surfaces 12, 12a upstand from the aforesaid wall 11, these wall surfaces being disposed substantially in parallel relation and supporting an axle pin upon which a snuffer lever 14 is mounted for free pivotal movement. The wall 11 has a wick tube 15 secured thereto substantially at right angles, this wick tube, therefore, being disposed within the chamber formed by the wall surfaces 12, 12a and said wick tube receiving the outer end of a wick 16 which extends to the interior of the fuel casing C1 where 70 it is surrounded by suitable material 17 for ab-

5 sorbing the fuel which is introduced into said fuel casing C1 when the cap 17a is removed. The lever 14, at its free end, carries a snuffer cap which is adapted to coact with and seal the wick tube 15.

6 A pair of side-by-side wheels 18 and 19 are freely rotatable on the axle pin 13, the wheel 18 being a wheel having a serrated outer surface and the wheel 19 being a ratchet wheel, these wheels being suitably secured together for movement as a 10 unit. Coactable with the serrated wheel 18 is a pyrophoric element 20 which partly projects from a tube 21 extending through the fuel casing C1, said tube 21 containing a spring 22 which is maintained under compression by a cap member 23 15 so as to bias the pyrophoric element 20 into engagement with the serrated wheel 18. As clearly appears from a consideration of Fig. 3, the serrated wheel 18 and the pyrophoric element 20 are so related that quick rotation of said wheel 18 in 20 a clockwise direction, Fig. 3, causes a shower of sparks to be directed toward and into engagement with the exposed end of the wick 16 when the snuffer cap is removed from the wick tube 15.

25 The snuffer lever 14, on its opposite sides, has 25 the respective pinions 24, 24a suitably secured thereto, these pinions meshing with the respective rack members 25, 25a projecting laterally from the end of a lever 26 pivoted at 27 in a pocket formed in the fuel casing wall 10, said lever 26 30 being suitably biased in a clockwise direction, Fig. 3, as by the spring 28.

35 The application of manual pressure to the lever 26 so as to effect movement thereof in a counter-clockwise direction, Fig. 3, causes clockwise 35 movement, Fig. 3, of the pinions 24, 24a and the snuffer lever 14 whereby the snuffer cap is elevated from the wick tube 15 so as to expose the outer end of the wick 16. During such movement of the snuffer lever 14, a suitable pawl arrangement, or equivalent, produces clockwise 40 movement, Fig. 3, of the serrated wheel 18 whereby a shower of sparks are passed into engagement with the now exposed end of the wick 16 to light the fuel carried thereby and producing a 45 freely burning flame such as shown in Fig. 2. When this flame has served its intended purpose, pressure on the lever 26 may be released whereupon the spring 28 moves the same in a clockwise direction, Fig. 3, to thereby cause counter-clockwise movement of the pinions 24, 24a and the snuffer lever 14 whereby the snuffer cap is reseated upon the wick tube 15 to extinguish the flame and to seal said wick tube so as to prevent evaporation of fuel. During the last described 50 movement of snuffer lever 14, the above noted pawl arrangement, or equivalent, permits the serrated wheel 18 to remain stationary.

55 In a preferred form of the invention as herein illustrated, the dimensions of the container C are such that a desired number of cigarettes A may be supported therein as illustrated in Fig. 3. Accordingly, with the combined device held with its long axis in substantially horizontal position as shown, the casing C1 may be moved in the manner hereinbefore described to open the container cover 2. Then while thus held, a cigarette A may readily be removed from the container and placed between the lips of the smoker, the combined device, while remaining in substantially the horizontal position as shown, thereupon being elevated toward the end of the cigarette so that the lighting mechanism may be operated in the manner hereinbefore described to produce a flame for the ignition of the cigarette. As will readily be 60 65 70 75 80 85 90 95 100

understood, the relation of the lighting mechanism to the cigarette container, particularly the arrangement for producing a flame having its long axis substantially at right angles to the direction of movement of the container cover or substantially parallel with respect to the cigarettes as stocked in the container, results in the production of a device which may be used in a convenient and efficient manner as described.

10 Aside from the foregoing, it is of distinct importance, in connection with my invention, that the casing C1, besides serving in the usual manner for supporting the lighter mechanism and supplying of fuel thereto, also has the important function of providing latching means for the cover of the cigarette compartment.

Further in connection with the advantages discussed immediately above, it is noted that, by my present invention, the lighter mechanism and the cigarette container, in effect, are separate units which are connected together by the spring 8 which, if desired, may be readily removable to permit separation of said units. Obviously, with such an arrangement, if the latching function of the fuel casing C1 is not considered necessary, the spring 8 may be replaced by a simple non-resilient arrangement which connects the container and casing together and which is detachable if desired. The characteristics of the invention last discussed are of distinct importance from the manufacturing viewpoint.

Aside from the foregoing, the particular type and arrangement of the lighting mechanism presents certain obvious advantages. Furthermore, with the disclosed arrangement, the fueling operation may be proceeded with in such manner that there is little possibility of the fuel reaching the cigarettes in the cigarette compartment. Moreover, the caps 17a and 23 are as conveniently located as if the lighter were a separate unit. Still further, from the viewpoint of adequate fuel capacity, it is desirable for the fuel casing to have a height substantially the same as that of the cigarette container.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In combination, a cigarette container having a pivoted cover, a pyrophoric lighter having a fuel casing pivoted to the fixed section of said cigarette container, latching means cooperable be-

tween said fuel casing and said pivoted cover, and means whereby pivotal movement of said fuel casing releases said latching means.

2. In combination, a cigarette casing, a cover therefor, a hinge for said cover extending along one edge of said casing, means for biasing the hinged cover toward open position, a pyrophoric lighter extending along the edge of said casing opposite from said hinge, means for interconnecting said casing and lighter whereby the lighter may be moved to a limited extent in respect to the casing, and cooperating means on said cover and said lighter for normally retaining the cover in closed position, said means being releasable upon movement of the lighter in respect to said casing.

3. In combination, a cigarette container having a pivoted cover, a pyrophoric lighter, resilient means for interconnecting said lighter and said container whereby said lighter may be moved to a limited extent in respect to said container, cooperating means on said lighter and said cover for latching said cover in closed position, said means being releasable upon such movement of the lighter.

4. In combination, a cigarette casing, a cover therefor, means for retaining said cover in closed position, a pyrophoric lighter disposed at one end of said casing, the length of said pyrophoric lighter being substantially the same as the width of said casing, said casing and said pyrophoric lighter having flat wall surfaces disposed adjacent each other, and means mounting said lighter on said casing whereby the lighter may have limited movement with respect to the casing, said means including a connection extending from the wall surface of the pyrophoric lighter to the interior of the casing, said last named means being so constructed and arranged that movement of said pyrophoric lighter releases said retaining means.

5. A combination lighter and container for cigarettes and the like, having casing sections pivotally connected together to form a container of the character above set forth, a lighter mechanism, means mounting said lighter mechanism upon one of said casing sections to afford limited movement of said lighter mechanism from one position to another with respect to said last mentioned casing section, said lighter mechanism having a latching member positioned to engage another of said casing sections when the lighter mechanism is in one position, to hold said casing sections in closed relation; and said last mentioned member being movable out of engaging relation with said other casing section when the lighter mechanism is moved away from said last mentioned position, to release said casing sections for pivotal movement one with respect to the other.

LOUIS V. ARONSON.
